(57) **CLAIM**

The ornamental design for a blender base, as shown and described.

DESCRIPTION

FIG. 1 is a perspective view of a blender base showing my new design;

FIG. 2 is a front elevational view thereof;

FIG. 3 is a rear elevational view thereof;

FIG. 4 is a top plan view thereof; the bottom plan view not being shown as it is devoid of ornamentation; and,

FIG. 5 is a left side elevational view of thereof.

The broken lines shown in the Figures are used for illustrative purposes only and form no part of the claimed design.
